UNITED STATES PATENT OFFICE.

HENRY HOVLAND, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

CALLING DEVICE.

1,171,520.

Specification of Letters Patent. Patented Feb. 15, 1916.

Application filed February 12, 1915. Serial No. 7,659.

To all whom it may concern:

Be it known that I, HENRY HOVLAND, a citizen of the United States, residing at East Orange, in the county of Essex and 5 State of New Jersey, have invented certain new and useful Improvements in Calling Devices, of which the following is a full, clear, concise, and exact description.

This invention relates to improvements 10 in calling devices for automatic telephone systems, and more particularly to a controlling device of the class adapted to receive and count impulses which are generated or produced at the selector which is for the 15 time being under the control of said device. In such systems impulses are sent from a central station on the one hand to the calling device located at the telephone substation, and on the other hand to automatic 20 selector switches located at the central and by means of which a connection may be established between a calling and a called subscriber. An impulse mechanism provided in the calling device counts off the impulses 25 sent from the central station, means being provided to prevent the sending of more impulses than predetermined by the movable or setting member of the calling device.

30 According to one feature of the invention, the movable or setting member is locked against actuation after it has been set and is unlocked only after the desired effect of the impulses, *i. e.* the moving of the automatic switch to a desired position, has been 35 accomplished. Due to this locking of the setting member during the operation of the impulse counting mechanism, the operator cannot interfere with the proper sending of 40 impulses by actuating the setting member before the counting-off of all the impulses.

Another feature of this invention relates 45 to means for locking the impulse counting mechanism during the setting of the movable or setting member and also while the device is in its normal position.

In the drawings, the calling device is 50 represented in connection with an automatic telephone system in which the subscriber controls the setting of the selector switches, only as much being shown of the circuit arrangements and selector switches 55 as is necessary for the understanding of this invention. It will be apparent, however, that the calling device forming the

subject matter of this invention may readily be adapted for use with systems of widely varying character, such as for instance semi-automatic telephone systems, electric signaling systems, etc.

Figure 1 is a perspective view of the calling device with parts broken away so as to show the interior mechanism of the device; Fig. 2 represents a top view of the calling device; Fig. 3 a sectional view along lines 3—3 of Fig. 7; Fig. 4 is a sectional view along lines 4—4 of Fig. 7; Fig. 5 is a sectional view along lines 5—5 of Fig. 7; Fig. 6 is a side elevation partly in perspective; Fig. 7 is a sectional view along lines 7—7 of Fig. 6; Figs. 8 and 12 show the escapement and locking mechanism; Figs. 9, 10 and 11 show details of the locking mechanism; Figs. 13, 14, 15 and 16 show the impulse sending mechanism in different positions during the operation of the sender; Fig. 17 shows the sender mounted in the base of a desk telephone stand; and Fig. 18 represents diagrammatically the connections between the subscriber's station and the central office.

The various parts of the device are mounted on a frame 1, through the center of which is extended a shaft 2. A plate 4 carrying numerals 1 to 0 is secured to shaft 2 by means of a screw 3 in such a manner that the shaft may revolve with respect to plate 4. A projection 5 of number plate 4 is fastened to frame 1 by means of screw 6. This projection 5 serves as a stationary stop for the finger of the operator to limit the forward movement of a dial 7. Around the periphery of dial 7 a continuous series of finger holds 8 are provided. Dial 7 is secured by means of a screw 9 to hub 10 mounted on the end of shaft 2, and may be moved by means of the finger holds in a clockwise direction. Rigidly mounted on the hub 10 is a star-wheel 12. Loosely mounted on shaft 2 is a star-wheel 13 carrying a member 14. Between the long projection 15 and short projection 16 of member 14 is provided a fork-shaped member 17. The fork-shaped member 17 rests on the star-wheel 13 and is carried on a pivot-pin 18 extending from star-wheel 19 through an opening of star-wheel 13.

Star-wheel 19 is mounted on the top of a cup-shaped gear wheel 23 loosely mounted on shaft 2. On the bottom of said wheel 110

23 is fastened a notched wheel 24. The cup-shaped wheel 23 incloses a power means, as for instance a motor spring 25, one end of which is fastened to the wheel itself and the 5 other end to shaft 2.

Pivoted in frame 1, by means of pin 26, is a pawl 27 carrying a roller 28 and a member 29. Pawl 27 is adapted to engage the notches of wheels 12, 13, 19 and 24. The 10 actuation of pawl 27 is controlled by a lever 31 mounted on shaft 2 below dial 7. A bent-down portion of lever 31 is connected by means of a pin 32 with a movable lever 33. The other end of lever 33 is secured to shaft 15 34 extending from frame 1; shaft 34 carries also a lever 35. On the free end of lever 35 is mounted a roller 36. Spring 37 is fastened at one end to frame 1 and at the other end to lever 35, and keeps lever 35 with its 20 roller 36 in engagement with a projection 37 of member 29 forming a part of pawl 27. In this position of roller 36, pawl 27 and roller 28 are kept out of engagement with the notches of wheels 12, 13 and 19, and projection 38 of member 29 is kept in one of its notches of wheel 24 as shown in dotted lines on Fig. 9. Upon the actuation of lever 31, roller 36 rides on the periphery of member 29 and causes pawl 27 to engage notches 25 30 of the notched wheels as will be described later. In its extreme forward position, roller 36 is pressed by member 29 against a projection 40 of contact spring 41. Movable mounted on member 29 is a member 42, 35 which, when engaged by a lever 43, releases roller 36 to its normal position.

Mounted on bridge 44 by means of screws 45-45 is a U-shaped electromagnet 46 having two pole pieces 47 and 48. Each leg of 40 electromagnet 46 carries an energizing coil 49 and 50 respectively. Pivoted in yoke 51 of electromagnet 46 is a shaft 52 carrying armature 53. Armature 53 is transversely pivoted between the pole pieces, as shown 45 in Fig. 5. Coiled spring 54 tends to maintain the armature 53 in contact with adjusting screw 55, and causes the armature to return to this position when released by the electromagnet. Pivoted between the frame 50 1 and a projection 56 to bridge 44 is a shaft 57 carrying a pinion wheel 58 and a rod 59. The pinion wheel 58 is intermeshing with gear wheel 23. Rod 59 and member 61 provided on armature 53 coöperate in such a 55 manner that, due to the movement of armature 53 in response to the intermittent energization of pole pieces 47 and 48 and the action of spring 54, wheels 24, 23 and 19 are moved step by step under the control of motor spring 25. In its initial position rod 59 engages, for instance, the outer surface of the short bent-up portion of member 61. Upon the attraction of armature 53 by pole 60 pieces 47 and 48, rod 59 is released by the shorter bent-up portion of member 61, and

rotates until it engages the inner surface of the longer bent-up portion of member 61. Upon the deenergization of the electromagnet, armature 53 is returned to its initial position by coiled spring 54, and thereby rod 70 59 is released by the longer bent-up portion of member 61 and again engages the outer surface of the shorter bent-up portion of member 61. Under the control of the escapement arrangement (comprising armature 75 53, member 61 and rod 59) the impulse counting mechanism, (i. e. wheels 24, 23 and 19) is stepped in accordance with the set position of the dial, as will be hereinafter described. 80

The subscriber desiring to initiate a call removes his receiver from its switchhook, closing thereby an energizing circuit for relay 65 from grounded battery at the exchange through the left-hand winding of 85 relay 65, back contact 66 and armature 67 of relay 68, and then at the substation through switchhook 69, contact 70, winding 71 of the induction coil, transmitter 72, normally closed springs 73 and 74 of 90 the calling device, and back to earth at the exchange through armature 75 and back contact 76 of relay 68. Relay 65 upon energization closes a circuit from earth through its armature, front contact and right- 95 hand winding, and winding of relay 68 to grounded battery 77. Relay 68 is energized and opens the original energizing circuit of relay 65. Relay 65, however, is maintained energized by current flowing in the circuit 100 established through the right-hand winding of this relay. Relay 68 closes also an energizing circuit for relays 78 and 79 from grounded battery 80, through the winding of relay 78, front contact 81 and armature 105 67 of relay 68, subscriber's loop through springs 73 and 74, armature 75 and front contact 82 of relay 68, conductor 83, armature and back contact of relay 86, and winding of relay 79 to earth and back to battery. 110 Relay 78, by attracting its left-hand armature, short circuits relay 65 through armature 87 of relay 68 and maintains relay 68 energized, the original circuit of this relay being opened upon the release of relay 65. 115 By attracting its right-hand armature, relay 78 closes an energizing circuit for magnet 89 of a sequence switch 84 through the left-hand armature and back contact of relay 90.

Only the power magnet 89 and contact 120 springs 91 to 95 are shown (in Fig. 17) of sequence switch 84. By means of magnet 89 and a clutch mechanism 96 a rotatable shaft 97 on which a plurality of cams are provided, is brought into engagement with 125 a constantly revolving power means 98 and is rotated thereby. The cams are arranged to actuate contact springs 91 to 95 in certain positions of the shaft. The positions in which the cams actuate springs 92, 93, 94 130

and 95 are indicated by numerals adjacent to the springs, and the numerals adjacent to spring 91 indicate in which position of the shaft 97 this spring is not actuated. Although only a few elements of the sequence switch are represented in the drawings and the springs are not shown in their structural relation to the switch, the operation of this device will be readily understood, sequence switches of similar types being well known, for instance, in electric signaling, in automatic telephone systems, etc. Upon the closure of the above circuit for power magnet 89, the sequence switch 81 is moved out of its first position into its second position. The subscriber can now proceed to set his calling device in accordance with the digits of the desired subscriber's number.

If the subscriber desires to send out, for instance, a series of five impulses, he engages with his finger a finger hold which is opposite number 5 on number plate 4 and rotates dial 7 in a clockwise direction. Star-wheel 12 rotates with the dial. When star-wheel 12 leaves its normal position, the fork-shaped member 17 is also moved by means of a pin 100 projecting from star-wheel 12 and positioned between the arms of the fork-shaped member 17. A pin 101 provided on the shorter arm of the fork-shaped member 17 engages the periphery of the opening 20 provided in star-wheel 13. The fork-shaped member 17 and the star-wheel 13 will thus be moved upon the actuation of the dial until the shorter arm of the fork-shaped member reaches the projection 16 provided on star-wheel 13. The pin 100 is now removed from between the arms of the fork-shaped member 17 and continues its travel with star-wheel 12 as it is clearly shown in Fig. 14. Pin 101 travels over half the periphery of opening 20 during the movement of fork-shaped member 17, and this member being pivoted at 18, star-wheel 13 is displaced. The position of star-wheel 13 with respect to star-wheel 19 is now such that their notches are no more in alignment, but present a smooth surface on their peripheries. During this movement of dial 7 and wheels 12 and 13, wheels 19, 23 and 24 remain in their normal position, due to the above described co-operation of the projection 38 of member 29 with the notches of wheel 21 and of rod 59 with member 61 provided on the armature 52 of electromagnet 56.

Shortly before the operator's finger reaches the finger stop 5, lever 51 is engaged and causes the bell crank lever arrangement 33, 35 to initiate. When the stop 5 is reached, ridge 36 of lever 35 is resting on projection 40 of spring 41, pressing this spring into engagement with spring 73 and urging spring 73 to disengage contact spring 74. As above described, this move-

ment of the roller 36 actuates pawl 27, which will engage a tooth of wheel 12 and lock this wheel until roller 36 is resting on projection 40 of spring 41. Due to the displacement of star-wheel 13, pawl 27 cannot engage star-wheels 13 and 19, but will rest with its roller 28 on the periphery of these wheels until star-wheel 13 is brought back into its normal position. Upon the actuation of pawl 27, projection 38 of member 29 is also removed from the notch of wheel 24, unlocking thereby the impulse counting mechanism, *i. e.*, wheel 24 and the wheels connected therewith. The calling device is now in a position to control the moving of a switch at the exchange to a terminal representing digit 5, *i. e.*, to count off five impulses. When contact springs 73 and 74 were separated at the substation, relay 79 became de-energized; relay 78, however, being slow acting remained energized, until a circuit was closed from grounded battery 89 through coil of relay 78, front contact 81 and armature 67 of relay 68, switchhook 69, contact 79, winding 71 of the induction coil, 90 transmitter 72 and contact springs 73 and 41 to earth at the substation and back to battery. Sequence switch power magnet 89 being at this time in its second position, relays 99 and 86 became energized being included in a circuit from battery 105, through the winding of relay 90, sequence switch spring 93 in position 2, winding of relay 86 and back contact and armature of relay 79 to earth.

Relay 90 closes a locking circuit for itself from grounded battery 105, through its winding, right-hand front contact and armature and sequence switch spring 94 to earth at repeating coil 106. Relay 90 closes also a circuit to drive the sequence switch out of its second into its third position from earth through right-hand armature and front contact of relay 78, left-hand armature and front contact of relay 90, sequence switch spring 92 and power magnet 89 to grounded battery.

In position 3 of the sequence switch, power magnet 107 of switch 108 is energized, a circuit being closed from earth through right-hand front contact and armature of relay 78, left-hand armature and front contact of relay 90, sequence switch spring 92, coil of magnet 107 to grounded battery. Upon the energization of magnet 107, pawl 109 presses rod 110 against a constantly rotating roller 111, and causes thereby brushes 112 and 113 to travel upward. Brushes 112 travel over a contact bank 114 in which trunks or subscribers' lines terminate, and brush 113 travels over an interrupter plate 115.

Relay 86 upon energization closed a circuit from grounded battery 116 through its front contact and armature, conductor 83, 130

- 4
- front contact 82 and armature 75 of relay 68, coils of magnet 46 at the substation, and contact springs 73 and 41 to earth and back to battery. Relay 86, however, was not energized for a sufficient length of time to cause the actuation of magnet 46, its circuit being opened at spring 93 as soon as the sequence switch left its second position.
- When wiper 113 of switch 108 reaches the first conducting segment 117 of interrupter 115, a circuit is closed from grounded battery 118 through the frame of interrupter 115, conductor 119, sequence switch spring 93 (in position 3), coil of relay 86 and back contact and armature of relay 79 to earth and back to battery. Relay 86 is again energized, and by attracting its armature closes the above traced energizing circuit for magnet 46 provided in the subscriber's calling device.
- This magnet becomes now energized and attracts its armature 53, allowing rod 59 to disengage the outer surface of the shorter arm of escapement member 61 and to engage the inner surface of the longer arm of said member. Rod 59 and the pinion wheel 58 perform, during this movement of the armature 53, half a revolution, and will cause the impulse mechanism, comprising wheels 24, 23 and 19 engaged by pinion 58 through ratchet wheel 23, to move a distance equal to one space between the centers of adjacent notches on wheel 24, which distance is equal to that between one finger hold 8 on dial 7.
- Relay 86 is intermittently deenergized and energized as cam 113 of switch 108 travels over conducting and non-conducting segments of interrupter plate 115. In response to each energization of relay 86, magnet 46 in the calling device is actuated and causes through the agency of the escapement mechanism, the stepping of the impulse mechanism in the above described manner. When wiper 113 passed over the fifth conducting segment of interrupter 115 and wipers 112 are resting on the fifth row of terminals 114, representing digit No. 5, magnet 46 causes the impulse mechanism to perform the fifth step.
- When magnet 46 received the fourth impulse, star-wheel 19 was brought to a position in which pin 100 of star-wheel 12 again engages fork-shaped member 17. During the fifth step of star-wheel 19 the fork-shaped member is again moved, but now in the opposite direction of its first movement. The longer arm of fork-shaped member 17 engages now projection 15 of member 14 provided on wheel 13 and causes the restoration of this wheel to normal. After the impulse sending mechanism has been moved a distance equal to 5 finger holds 8 on dial 7, i. e., five steps, the notches of star-wheels 19 and 13 are again in alinement, allowing roller 28 of pawl 27 to fall into the notches of these wheels as it is shown in Fig.
10. The member 29 of pawl 27 no longer presses roller 36 of lever 35 against the projection 40 of spring 41, and said roller is released thereby to its normal position, allowing spring 41 to disengage spring 73 and 70 spring 74 to engage this latter spring. As roller 36 bears now against projections 37 of member 29, pawl 27 is caused to unlock wheels 12, 13 and 19 and to lock, by means of projection 38, wheel 24. Lever 31 is restored to normal together with roller 36 i. e. lever 35. Dial 7 remains in the position to which it was moved by the operator. Any one of finger holds 8 may be opposite any numeral on plate 4, a continuous series of 80 holds 8 being provided on dial 7. Relay 86 being deenergized at this time, as soon as contact spring 73 engages contact spring 74 the circuit of relay 79 will again be established. Upon energization relay 79 closes 85 through its front contact and sequence switch spring 95 an energizing circuit for magnet 89 and causes sequence switch 84 to move out of its third position. The sequence switch being moved out of its third position, power magnet 107 of switch 108 is deenergized, and the switch arrested thereby with its wipers in contact with the fifth row of terminals on bank 114.
- If the operator finds after the dial 7 is set 95 that the selected finger hold was not the right one, he can prevent the operation of the impulse mechanism by hanging up his receiver on the switchhook. In this case, rod 120 engages, through the agency of 100 lever arrangement 121, lever 43 of the calling device. Lever 43 is pivoted at 122 and upon actuation engages with its projection 123 a projection 124 on the movable member 42 provided on 29 of pawl 27. Member 42 105 being moved downward releases roller 36 from projection 40 of spring 41 in the same manner and with the same effect as it is described above in connection with member 29. On the other hand, projection 125 of lever 43 engages armature 53 of electromagnet 46 and prevents thereby the operation of the escapement mechanism. The operator can in the same manner prevent the further 110 actuation of the impulse mechanism at any 115 stage of operation thereof.
- What is claimed is:
1. In a calling device, a movable member, a power means adjusted responsive to the movement of said member, an impulse counting mechanism adapted to be controlled in accordance with the set position of said member, an electromagnet for controlling said mechanism, means for locking said impulse counting mechanism while said member is 120 moved, and means for locking said member while the mechanism is moved.
  2. In a substation calling device for automatic telephone exchanges, a dial provided 125 with an endless series of finger holds, a sta- 130

- tionary plate carrying numerals each of which may be opposite any one of said finger holds, a motor spring wound up by the actuation of said dial, a notched wheel locked 5 during the actuation of said dial, a pivoted pawl for locking said dial in its actuated position, an electromagnet, means controlled thereby for moving said notched wheel, and means operative after said notched wheel 10 has been moved a distance determined by the movement of the dial for unlocking said dial and for locking said notched wheel.
3. In a calling device, a dial having a plurality of operating positions, finger holds 15 for actuating said dial, a lever adapted to be actuated by engagement with the finger in a finger hold, means operative thereby to hold said dial locked when moved to any of its operating positions, an impulse counting 20 mechanism, an electromagnet to control said mechanism, and means controlled from a distant station and operative upon the locking of said dial to actuate said electromagnet.
4. In a calling device, a movable member, 25 a power storing mechanism connected with said movable member and adapted to be adjusted responsive to movement of said member, an impulse counting mechanism, an electromagnet, means for locking said member 30 whenever said mechanism is unlocked and for locking said mechanism whenever said member is unlocked, and means under the joint control of said power storing mechanism and said electromagnet for operating 35 said impulse counting mechanism.
5. In a calling device, a number plate, a forwardly moving finger hold dial, a notched wheel fixed thereto, a locking member, a movable lever adapted to be engaged 40 by the finger when in a finger hold, a stationary stop, said lever when engaged by the finger upon actuation of the dial controlling said locking member to engage said notched wheel to lock the dial, an electromagnet, an 45 impulse counting mechanism controlled thereby after the locking of said dial, and means for unlocking said dial after said mechanism has operated.
6. In a calling device, a movable member, 50 a series of finger holds for actuating said member, contact springs, an electromagnet, an impulse counting mechanism, a lever actuated by engagement with the finger in a selected finger hold, means controlled by 55 said lever for locking said impulse counting mechanism in the normal position and during the actuation of said movable member, power means stored up during the actuation of said member, and means controlled by 60 said lever to apply said power means to said impulse counting mechanism and to lock said member during the operation of said mechanism.
7. In a calling device, a movable member having a plurality of operating positions, an impulse mechanism adapted to be actuated in accordance with the set position of said member, a pair of relatively movable star-wheels comprised in said impulse sending 65 mechanism, a pawl adapted to lock said mechanism when the dial is in the normal position and during its movement to an operating position and to lock said dial while said mechanism is actuated, the locking of said mechanism being prevented while said 70 star-wheels are in a relatively displaced position.
8. In a calling device, a movable member, an impulse counting mechanism locked during the actuation of said member, means for 80 unlocking said mechanism and locking member after the latter has been set to the desired position, an electromagnet, means controlled thereby for stepping said mechanism in accordance with the set position of 85 said member, means operative thereafter for unlocking said member, and means controlled by the operator for preventing the stepping of said mechanism and for unlocking said dial at any stage of operation of 90 said impulse counting mechanism.
9. In a calling device, the combination with a revolvable dial having a plurality of operating positions, a series of adjacent finger holds for actuating said dial, coöperative 95 contacts, a lever adapted to be actuated by engagement with the finger in a finger hold, means controlled by said lever for simultaneously locking said dial against further actuation when moved to any of its operating 100 positions and for actuating said contacts, an electromagnet, an impulse counting mechanism controlled thereby, means for controlling said electromagnet when said contact springs are actuated and means for unlocking 105 said dial, locking said mechanism and releasing said contact springs after the impulse counting mechanism has operated in accordance with the set position of said dial.

In witness whereof, I hereunto subscribe 110 my name this 9th day of February A. D., 1915.

HENRY HOVLAND.
